BUILDING BLOCK

William A. Blanding, Jr., Belding, Mich.

Application November 26, 1940, Serial No. 367,210

6 Claims. (Cl. 46—25)

This invention relates to interlocking building blocks.

The principal object of the invention is to provide a set of building blocks which includes a large number of blocks of separate and distinct shapes and sizes, so constructed that the blocks may be locked together in different combinations of three or more to form a wide variety of structures.

Another object of the invention is to provide a set of building blocks capable of being assembled in interlocking relationship without the use of separate key blocks.

Another object of the invention is to provide a set of building blocks which can be readily assembled and disassembled, and which when assembled form a stable composite structure.

These objects are attained by providing a set of a large number of blocks, all of which have the following features in common:

1. Each block is formed in one piece but comprises one or more fundamental L-shaped sections, all of said sections being the same size.

2. All blocks are provided with right parallel-epipodal projections of the same thickness.

3. The lengths of the blocks are multiples of the lengths of the shortest of the above mentioned projections.

The foregoing objects will more fully appear in the foregoing specification when read in connection with the accompanying drawing, wherein—

Figure 1 is a perspective view with parts broken away of one structure formed from the set of blocks comprising this invention;

Figures 2 to 19 are pictorial views of the respective individual blocks which make up the set comprising the invention; and

Figures 20 to 23 are pictorial views illustrating the manner of assembling certain of the blocks together.

In the following description and in the claims the word "length" indicates a dimension taken in the direction indicated by the letter L in Figure 2. Similarly, "width" and "height" indicate dimensions taken in the directions indicated by the letters W and T respectively. Thus, the length of a block or a part thereof may be less than its width or height.

The blocks which comprise this invention may be divided generally into three groups. Group 1 includes blocks A to I, shown in Figures 2 to 11, and may be called the wall blocks. Group 2 consists of blocks J, K and L, shown in Figures 12 to 14, which are step blocks, and group 3 includes

roof blocks M, N and O, cornice block P, and chimney base block Q, shown in Figures 15 to 19 respectively.

All upright structures, such as walls and the like, are formed by various combinations of the blocks of Group 1. All of these blocks have the same overall width and the same overall height. Preferably their width is twice their height. All of them are provided with cooperating projections and recesses so formed that any three of the blocks may be secured together in interlocking relationship.

It will be noted from the drawing that each of blocks A to I comprising group 1 is composed of one or more L-shaped sections 10 which may be termed the "fundamental sections." All such fundamental sections are identical in size and shape. They are defined in the drawing by the exterior surfaces of the blocks and the planes formed by the broken lines in Figures 2 to 11.

Block B is the smallest block, and all other blocks of group 1 are multiples of it in length. This block is composed of two of the L-shaped sections above described arranged back to back. The upright legs of the L-shaped sections 10 form a pair of oppositely extending projections 11 at one end of the block. Adjacent the projections 11 at the other end of the block are angular recesses 12, the bottoms of which are formed by the horizontal legs of the L-shaped sections 10.

Since the L-shaped sections are equal in size and shape, it follows that the projections 11 are equal in length, width and height. The length, width and depth of each recess 12 are equal to the length, width and height respectively of each of the projections 11. The length of the block B is twice the length of the projections 11.

Block A is the most frequently used of all of the blocks of the set. It is composed of four L-shaped sections arranged as shown in Figure 2, or in other words, is shaped like two of the blocks B arranged end to end. This block has two pairs of oppositely extending projections 11 at the ends of the block separated by recesses 13 of a length twice that of the projections 11. The length of the block is four times the length of the projections 11.

Block C is employed primarily to form the top or bottom of a window opening or the top of a door opening in a wall. It is composed of six L-shaped sections 10, four of them being located back to back at the ends of the block, and the other two arranged end to end in the middle of the block. Thus, the block has four projections

11 at the ends thereof and an intermediate projection 14 which is double the length of the projections 11. Intermediate the central projection 14 and the end projections 11 on one side of the block are recesses 13 of the same length as the recesses 13 in block A. On the opposite side of the block is a wide recess 15.

Blocks D and E are the base blocks for a wall structure. These blocks are composed respectively of one and two L-shaped sections respectively. The blocks D and E are similar to blocks B and A, respectively, but with the bottom recesses 12 and 13 filled up so that the blocks may rest on a floor or table without leaving any gaps.

Block F is another base block employed to form the bottom of a door frame. This block has two projections 11 at the ends and a wide recess therebetween. The length of the block is eight times the length of the projections 11.

Blocks G and G' are corner blocks for joining two walls at right angles to each other. Block G is of the same length, width and height as block A and has three projections 11 thereon, two at one end and one at the other. A fourth projection, designated by the numeral 16, is of the same length as the projections 11 but its width is equal to its length.

Block G' is substantially the same as block G but has a square projection 16', the same as 16 in block G, but located at the opposite corner. The blocks G and G' are used alternately in building the corner between the adjoining walls, see Figure 23.

Block H is employed in a manner similar to block C but is used to form a window or door opening of extra width. It is similar to block C, but longer, being twelve times the length of the end projections 11. It has two double length projections 14 on one side. The recesses 13 between the projections 11 and 14 are twice the length of the projections 11.

Block I is employed only at the top of a wall to support the eave blocks, which will be described presently. Block I has two projections 11 on the bottom side spaced apart by a recess 13. The length of the block is four times the length of the projections 11. On the top of the block is a projection 17 which extends the full length of the block at one edge thereof. The width and height of the projection 17 are equal to the length and height of the projections 11.

Blocks J, K and L, forming group 2, are used only for steps. Block J is the bottom or first step. Its length is six times the length of the projection 11 on the blocks previously described. This block is formed to fit around the ends of two base blocks E.

Block K is the same length as block J and has a projection on one side thereof extending the full length of the block. The width of this projection is equal to the length of projections 11. Block K rests upon block J and interlocks therewith.

Block L is the third or top step. This block is equal in length to block A and is of the same cross-section as block K. It fits into the wall structure between two adjoining blocks, such as blocks A.

The blocks of group 3 all have one or more inclined surfaces but they include the same fundamental L-shaped section as do the other blocks.

Block M is long enough to extend the full length of a house, such as is shown in Figure 1. On its lower surface it has a projection 18 which extends the full length of the block. The width

5 of the projection 18 is equal to the length of projections 11. At the other edge of the block is a recess 19 of a width equal to the length of recesses 12 previously described. Thus, the width 5 of the recess 19 is equal to the width of projection 18.

Block N is slightly wider than block M, but otherwise of the same cross section. The added width is provided by an elongated projection 20 10 at the side opposite the projection 18. This projection 20 forms an overhanging eave for a house structure, such as shown in Figure 1. The elongated recess 19 between the projections 18 and 20 receives the projections 11 on the top wall blocks I.

Block O is of the same cross-section as block M, but adjacent one end thereof is provided with a transverse groove or recess 21. This recess is adapted to receive the chimney base block which will be described presently.

Block P is of the same cross-section as block M. Its length, however, is equal to the width of the wall blocks forming group I.

Block Q is the chimney base block. It is 25 formed of two L-shaped sections 10 arranged in end to end relationship and has two triangular sections on its lower side. The two triangular sections form a V-shaped recess 22 which fits over the blocks O in the groove 21. The top surface of the block has a projection 14 and a pair of recesses 12 at opposite ends of the projection 14.

The manner of locking the blocks together is 30 illustrated in Figures 1, 20, 21, 22 and 23. The base blocks D, E and F are arranged in end to end relationship in any desired combination and where a corner is to be formed one of the blocks E is arranged with one end at the side of an adjacent block E. The wall is then built up of a plurality of sections, such as A, the latter being arranged in end to end relationship, so that a pair of projections 11 are received in the recesses 13 35 in the blocks E and F, and the projections 11 on the blocks E and F are received in the recesses 13 in blocks A. At the corners of the building, blocks G and G' are arranged in alternate relationship and are interlocked with base blocks E and with each other, as shown best in Figure 23. The projections 11, 16 and 16' on blocks G and 40 G' cooperate with similar projections on adjoining blocks A to lock the blocks together.

Blocks B, C, H and I are also fitted into the wall and interlocked in the same manner, but 45 are used around door and window openings and at the bottom of the wall, as necessary.

The use of the roof blocks is shown in Figures 20 to 22. Block N fits over the upstanding projections 17 on the blocks I and the projections 11 on blocks G and G' at the corners of the building. The aforementioned projections are received 50 in the recess 19 in the bottom of the block N.

The projections 18 on the lower sides of the blocks M are received in the recesses 13 in the top blocks A at the ends of the building. See 55 Figure 21.

There are two blocks O. These fit together in back to back relationship as shown in Figure 22, and the projections 18 are received in the recess 13 in the top block A at each end of the building.

The chimney base block Q seats in the recesses 21 in the blocks O. The chimney may be completed by fitting a base block B over the projection 14 on the top of the chimney base block Q,

or the chimney may be built higher with additional blocks A and B.

From the foregoing it will be seen that the blocks which comprise this invention are so constructed that they may be interlocked in a wide variety of ways. Furthermore, each block interlocks with one or more of the other blocks without the use of separate key blocks, such as have been considered necessary in previous sets of blocks. No gaps whatever appear in the completed structure except those for the windows, doors and the like.

This invention has been developed primarily as a toy. However, it will be evident that larger blocks involving the same fundamental principles may be constructed for the purpose of erecting full sized buildings of different sorts.

The scope of the invention is indicated in the appended claims.

I claim:

1. A set of building blocks including three blocks of different configurations, said blocks being formed with cooperating projections and recesses whereby the blocks may be secured in interlocked engagement, one of said blocks being of substantially greater length than its width and height, said block having a projection on one side at the edge thereof extending the full length of the block, the width of said projection being equal to the length of the shortest projection on any of the blocks.

2. A set of building blocks including three blocks of different configurations having the same overall width and the same overall height, said blocks being formed with cooperating projections and recesses whereby said blocks may be secured in interlocked engagement, one of said blocks comprising two oppositely extending projections of equal size at one end of the block and of a width equal to the width of the block, and two oppositely extending projections at the other end of the block, one of said last mentioned projections having a width equal to its length.

3. A set of building blocks comprising at least three separate blocks, each of said blocks being of a different configuration and each block being of the same width and overall height as the other blocks, at least two of said blocks being of the same length, one of said blocks comprising a projection extending from one face thereof at one edge thereof, the length of the projection being the same as the length of the block, each of said blocks having a projection on one face thereof at one end thereof, all of said last named projections being of the same shape and size, at least one of said blocks having two of said last named projections on one face thereof spaced to form

a recess therebetween of a dimension corresponding to the combined dimensions of two of said last named projections, whereby said blocks may be secured in interlocking engagement to form a wall structure of a uniform thickness equal to the width of said blocks.

4. A set of building blocks comprising at least four separate blocks, each of said blocks being of a different configuration and each block being of the same width and overall height as the other blocks, at least two of said blocks being of the same length, each of said blocks having a projection on one face thereof at one end thereof, all of said projections being of the same shape and size, at least two of said blocks having two of said projections on one face thereof spaced to form a recess therebetween of a dimension corresponding to the combined dimensions of two of said projections, whereby said blocks may be secured in interlocking engagement to form a wall structure of a uniform thickness equal to the width of said blocks.

5. A set of building blocks comprising at least four separate blocks, each of said blocks being of the same width and overall height as the other blocks, at least three of said blocks being of the same length, each of said blocks having a projection on one face thereof at one end thereof, all of said projections being of the same shape and size, at least two of said blocks having two of said projections on one face thereof spaced to form a recess therebetween of a dimension corresponding to the combined dimensions of two of said projections, whereby said blocks may be secured in interlocking engagement to form a wall structure of a uniform thickness equal to the width of said blocks.

6. A set of building blocks comprising at least three separate blocks, each of said blocks being of a different configuration and each block being of the same width and overall height as the other blocks, at least two of said blocks being of the same length, each of said blocks having a projection on one face thereof at one end thereof, all of said projections being of the same shape and size, at least one of said blocks having two of said projections on one face thereof spaced to form a recess therebetween of a dimension corresponding to the combined dimensions of two of said projections, at least one of said blocks comprising a pair of oppositely extending projections of equal size at each end of the block, whereby said blocks may be secured in interlocking engagement to form a wall structure of a uniform thickness equal to the width of said blocks.

WILLIAM A. BLANDING, Jr.
